UNITED STATES PATENT OFFICE

CLIFFORD T. RAULE, OF BROOKLINE, PENNSYLVANIA

CONTROL FOR INTERNAL GRINDERS

Application filed May 21, 1929. Serial No. 364,929.

My invention relates to multiple spindle precision grinding machines adapted to grinding duplicate work pieces to a definite dimension, as determined by automatic gauges upon the respective grinding units, each unit having a feed screw feeding the work to the wheel, or the wheel to the work, until the work is ground to size after which the wheel is automatically withdrawn from the work, my invention relating more specifically to the feed mechanism and the return thereof to its initial position, and to auxiliary safety devices.

A purpose of my invention is to provide an automatic quick-return of a feed screw to its initial position after having completed an operation upon one work piece, preparatory to loading another work piece into the machine thereby avoiding any danger of engagement between the end of a wheel and a work piece by reason of the feeding operation on a preceding work piece. I preferably use the movement of a gauge when the work piece has been finally brought to required size to effect the quick return in making or breaking an electric circuit, and preferably return the feed member to its initial position by means of a spring. I may also use the gauge as it approaches the unloading position of the machine to electrically stop the turn-table unless and until the piece has been ground to size and unless and until the wheel is out of the way for unloading and loading.

A further purpose is to combine an automatic loader with a quick return of the feed members of the individual units in order to bring the work and wheel of successive units into proper alignment for loading.

Further purposes will appear in the specification and in the claims.

My invention is adapted to many variant types of multiple spindle grinding machines, using different types of automatic gauges to limit the grinding operations upon successive work pieces and I have elected to illustrate it as applied to the type of machine disclosed and described in McDonough Patent No. 1,497,574, of June 10, 1924, entitled "Internal grinding machines," thus avoiding need for detail description of parts that are not in

themselves parts of my present invention. Of the many types of gauges that might be used I show two only, one of which is generally similar to that disclosed in the McDonough patent and the other generally in accord with that disclosed in my Patent No. 1,225,858, for Automatic sizing device.

Figure 1 is a fragmentary top plan view partially diagrammatic and shows my invention embodied upon one of the many types of multiple grinding machines to which it is well adapted to be applied; the view corresponding generally to Figure 2 of the McDonough patent above referred to but modified to embody features of my invention and for greater simplicity of illustration omitting some parts of the machine shown in the figure of reference.

Figure 2 is a detail elevation partly diagrammatic, illustrating structure embodying my invention, with auxiliary sizing gauge for controlling different operations made in accord with my invention.

Figure 3 is a detail elevation of feed and feed return mechanism embodying some features of my invention illustrating a different form of controlling sizing gauge from that shown in Figure 2, being a section upon the line 3—3 of Figure 4 in the direction of the arrows.

Figure 4 is a vertical section of Figure 3 taken upon the line 4—4 thereof.

Like numerals refer to like parts in all figures.

Describing in illustration and not in limitation, and referring to the figures:—

Referring to the multiple grinding machine shown, Figure 1 is intended for a conventional illustration of any machine to which the invention is adapted to be applied.

The turn-table 10 is rotatably mounted upon stationary supporting structure 11, lateral brackets 12 of the table carrying wheels 13 which roll round upon a suitable circumferential track 14 of the supporting structure.

Grinding units are mounted at spaced intervals around the table, each unit comprising a work-holder 15 and a grinding wheel unit 16 (only one of each shown in Figure 1).

The wheel units with wheels rapidly revolving, traverse at variant heights in vertical guides 17 of the turn-table which carries the work-holders beneath the respective wheel units, the wheel units being adapted 5 to traverse grind to definite size work pieces 18 in the respective work-holders.

The turn-table is driven by belt 19, pulley 20, shaft 21 and a friction drive disc 22.

The shaft 21 is journaled in suitable bearings 23 at the side of the supporting structure and the periphery of the disc 22 engages the face of a friction wheel 24 that is adapted to rotate the turn-table by mechanism not shown and irrelevant to the present invention. The disc 22 is illustrated as adjustable along its shaft at 25 to vary the rate of rotation of the friction wheel 24.

The work-holder and wheel units may be 20 operatively connected to mechanisms driven by the friction wheel 24—or otherwise as desired, but the drive of the turn-table is desirably independent of that of the wheel and work-holder units and such as to permit 25 stopping rotation of the turn-table without interrupting traverse grinding. Most of the mechanism shown in Figure 1 is described in detail in the McDonough patent referred to.

Work pieces are fed into the successive 30 work-holders by any suitable loader 26 that remains at one position, feeds the work pieces into the holders as they pass and that preferably operates automatically.

The pieces are unloaded after having been 35 ground to size and having made almost complete circuit of the machine by discharge mechanism 27 that preferably operates automatically and is placed some little distance before the loader 26.

Both the loading and unloading mechanisms 40 may be of any suitable types, as for example such as are already described and claimed by me in one or more copending applications, and are illustrated here diagrammatically, the actual mechanisms being irrelevant to the present invention.

The work-holders are loaded with new pieces as they pass the loader 26 and after 50 they are loaded traverse grinding begins and continues with a gradual feed between the work and wheel units until the pieces are ground to size as determined by individual gauges that may be mounted either upon the individual wheel units above the work pieces 55 or upon the individual work-holders beneath the work pieces.

One type of gauge is illustrated at 28 in Figure 2 and the other type at 28' in Figure 3, and it is to be understood that each grinding unit includes one suitable gauge, of 60 either type.

Figure 3 indicates gauges 28' mounted upon the work-holders and generally similar to the gauges of the McDonough patent, while Figure 2 shows gauges 28 mounted

upon the wheel units that are generally similar to the gauges disclosed and claimed by me in my U. S. Patent No. 1,225,858 referred to.

The gauges 28' of Figure 3 are all alike 70 each including gauge pins 29 and 30 mounted transversely in the upper end of a vertically guided and upwardly pressed gauge carrier 31 that is continuously coaxial with the work piece 18.

The carrier 31 is pressed upwardly by the upper end of a plunger 32 that is slidably mounted in a tubular guide 33 telescoping into a downwardly directed bore of the carrier the guide 33 being rigidly fastened to the turn-table. The plunger is pressed upwardly by a spring 34 inside the tubular guide and is provided with a downwardly extending stem 35 carrying a contact member 36 at its lower end.

The upper gauge pin 29 has a length slightly less than the desired bore of the finished work piece while the lower pin 30 has a length equal to the bore diameter of the finished piece.

Traverse grinding continues with a relative rapid feed between the wheel and work piece until the internal bore of the pieces has become sufficient for the upper gauge pin 29 to follow the traversing wheel upwardly into 95 the work piece, closing an electric circuit as described in the McDonough patent, to reduce the rate of feed.

Traverse grinding continues at the reduced 100 rate of feed until the internal diameter of the piece is such as to admit the lower pin 30 into the bore of the piece which closes a second circuit, also as disclosed by McDonough to stop the feed altogether and to raise the wheel out of the work piece.

The feed between the wheel and work piece 105 is most desirably automatic and in the McDonough type of machine is effected by screw adjustment of the position of the work-holder with respect to the wheel unit, a ratchet feed of the screw being operated by the traverse motion of the wheel.

The vertical traverse of the wheel unit vertically reciprocates a link 37 (Figure 3), to oscillate a rocker member 38.

The hub 39 of the rocker member is loosely mounted upon a shaft 40 that is journaled at 41 and 42 in structure of the turntable and carries a gear 43 which meshes with a gear on the end of a shaft 43' that is adapted to 115 operate the feed screw by intermediate mechanism not shown and irrelevant to the present invention.

Upper and lower arms 44 and 45 of the rocker carry pawls 46 and 47 adapted to engage ratchet teeth 48 around a wheel 49 keyed to the shaft.

Each time the grinding wheel 16 traverses up and down there is an oscillation of the rocker member 38 carrying the pawls 46 and 130

47 back along the ratchet teeth 48 during the down strokes and forward during the up-strokes to forwardly feed the ratchet wheel 49. The pawls are provided with adjustable shield members 50 and 51 to keep the pawls 5 during their forward strokes out of operative engagement with the ratchet teeth 48 except during the latter portion of the strokes, the effective strokes of the pawls being adjusted by changing the positions of the 10 shields.

The shields are placed to make the effective strokes of the upper pawl longer than those of the lower pawl.

Electric magnets 52 and 53 and cooperating 15 armature rocker members 54 and 55, spring-pressed from the magnets at 56 and 57 respectively are adapted to raise the pawls when the magnets are energized, which is accomplished by determinative movements of 20 the gauges 28 or 28' and cooperating electric circuits.

The sizing gauge 28 (Figure 2) is mounted upon the wheel unit and is generally similar to that disclosed and claimed in my Patent 25 No. 1,225,858, dated May 15, 1917, entitled "Automatic sizing device".

In the figure the spindle 58 of the wheel unit carries one or more pairs of spaced contact members 59, 60 and 61, 62 relatively adjustable at 63 and 64 respectively and mounted upon the upper ends of rocker members 65 and 66 that extend downwardly with the wheel into the interior of the work piece.

The rocker members are pivotally supported at intermediate points 67 and 68 upon a collar 69 fastened to a sleeve 70 that surrounds the high speed wheel spindle 58.

The rocker members are spring-pressed at 40 71 so as to tend to spread their lower ends.

During traverse grinding the suitably bulged lower ends 72 of the rockers slide up and down on the interior of the work piece, and gradually spread as the work piece is ground away, causing the opposing contact members on the upper ends of the arms to move toward one another until when the desired diameter has been reached the members 59 and 60 come together energizing the magnet 52 to reduce the rate of feed, after which 45 traverse grinding continues at the reduced feed until the contact members 61 and 62 come together when the piece has finally come to size, closing a circuit, or circuits, through 50 these contacts to energize the magnet 53 which stops the feed altogether and moves the wheel away from the work piece.

Most of the feed mechanism as thus far described is in the prior art and described in 55 greater detail in the McDonough patent above referred to.

I provide means for an automatic return of the feed wheel 49 to its original position after a work piece has been ground to size and 60 before a new work piece has been loaded into

the work-holder, and also means for stopping the turn-table if a grinding unit reaches any designated position, (usually a point just before unloading position) if the work piece of the unit is not yet ground to size, continuing the grinding while the turn-table is 70 stationary until the piece reaches finish size and then raising the wheel away from the work, starting the turn-table, and effecting spring-return of the feed screw.

Upon the shaft 40 which rigidly carries the feed wheel 49 I mount an auxiliary wheel 73 adapted to rotate upon the feed shaft 40 and spring-connected with the feed wheel 49 by means of a spiral spring 74. One end of this spring is fastened at 75 to the feed wheel and the other end at 76 to the auxiliary anchor wheel 73.

The anchor wheel 73 is externally V-notched at 77 to receive the bevel end 78 of 80 an inwardly pressing click member 79.

The click member is of square section forwardly beveled to fit the V-notches, longitudinally guided in a radial direction at 80, and internally bored from its rear end to receive the spring 81.

A screw 82 in the outer end of the guide member 80 projects into the bore of the click member to provide means for adjusting the effective strength with which the click member presses inward by suitably changing the compression of the spring 81.

The click member 79 maintains the auxiliary wheel 73 in any set position unless the strength tending to move the wheel is sufficiently great to push back the click member against the action of the spring 81. The notches around the wheel are the same so that the wheel may be held to position at any one of the clicks.

The feed and anchor wheels 49 and 73 are provided with cooperative stop members 83, 84 and 85 that are relatively adjustable and are used to permit variation of the initial spring tension between the wheels and to permit adjustably limiting the angular movement between the wheels.

As illustrated the stop 83 upon the anchor wheel is an abutment across a groove 86 in the face of projecting run 87 casing the spiral spring between the wheels, and the stops 84 and 85 are screw clamp members mounted along an arcuate slot 88 of the feed wheel and that project into the groove 86 from different positions around the feed wheel.

I obtain any desired initial tension between the feed wheel 49 and the auxiliary wheel 73 by winding the anchor wheel with respect to the feed wheel, then setting the stop member 84 on the feed wheel so that it is adjacent the stop 83 on the anchor wheel. I also set the second stop member 85 in position upon the other side of the member 83 so as to engage the stop 83 at the desired limit of arcuate movement between the two wheels.

In effect the three stops 83, 84 and 85 are two pairs of stops, the member 83 cooperating with the member 84 and also independently cooperating with the member 85. 5 Where it is desired to obtain wider angular movements between the feed and anchor wheels it will be desirable to keep the pairs distinct and at different radial distances from the axis of rotation so as to avoid interference between the stops 84 and 85. 10 The feed then takes place, as already described, resulting in an angular step by step rotary movement of the feed wheel, by reason of vertical reciprocation of the rod 37 which is suitably connected to the traversing wheel 15 unit.

Normally the anchor wheel does not move during the forward movement of the feed wheel, being held from movement by the click member, and an auxiliary pawl 89 prevents spring-return of the feed wheel 49 when the feed pawls 46 and 47 are both lifted from the feed wheel. 20

The pawl 89 is adapted to be raised from the teeth of the feed wheel by energizing a 25 magnet 90.

Normally there will be no movement of the auxiliary wheel 73 with respect to the click member after initial setting except at more 30 or less infrequent intervals due to wearing away of the wheel from repeated diamonding and grinding.

After a work piece has been ground to size determinative movement of the sizing gauge 28 or 28' with suitable electric connections 35 controlled by the movement of the gauge successively raise the pawls 46 and 47 from the teeth of the feed wheel which permits the feed wheel to spring back to its initial position, thereby avoiding any danger of the end 40 of the wheel striking the inner rim of the new work piece by reason of an inadvertent failure to return the feed wheel by hand or otherwise.

If the forward feed of the feed wheel is 45 greater than the angular distance between the adjustable stop 85 upon the feed wheel, and the fixed stop 83 upon the anchor wheel, these two stops engage and during any continued feed the two wheels move as a unit. 50

Normally the initial angular distance between these two stops is made merely sufficient to permit the maximum feed that may be needed with the work pieces to be operated 55 on, which are usually initially of variant and somewhat uncertain sizes, this being the lower limit of safety.

As the wheel wears away the angular movement of the feed wheel gradually increases 60 with successive work pieces until an engagement between the stops 85 and 83 advances the anchor wheel one or more notches at the click member which correspondingly lessens the return movement of the feed wheel to 65 merely that needed for safety.

I preferably do not return the feed wheel 49 to its initial position until the grinding unit, which includes the wheel unit 16 and work-holder 15, reaches a position just before that for unloading, and in the illustration provide connections for effecting the return of the feed wheel 49 always at the same point, preferably a position just before that for unloading and for automatically stopping the turn-table to permit completion of grinding if a unit comes to this position before its piece has been ground to size, starting the turn-table again as soon as the piece comes to size. 75

Suitable safety structure and connections 80 (Figures 2 and 3) insure that the grinding operations at the different units are always completed before the respective units reach the unloading position, by temporarily holding up the rotary movement of the turn-table if any unit reaches the designated point a little before the unloading position before completing its grinding operation. 85

A rocker member 91 is pivoted at 92 adjacent the turn-table 10 and has arms 93 and 94 of which 93 is connected, in any suitable way not shown, to control the operation of the turn-table, preferably without effecting that of the grinding units, and 94 extends radially inward toward the turn-table. 90

The rocker is spring-pressed at 95 against a stop 96, and when in position against the stop permits rotation of the turn-table, and when deflected away from the stop prevents rotary movement of the turn-table, as by effecting any suitable shift of gearing or belt. 95

The arm 94 of the rocker carries on its outer end a swinging armature member 97 that has outer and inner positions in which it is respectively adapted to engage and clear lugs 98 projecting from the turn-table at the 100 respective grinding units. 105

The armature member 97 is spring-pressed toward its outer position at 99, its outward movement being limited by suitable stop at 100. 110

An electromagnet 101 mounted upon the arm 94 pulls the armature member inwardly when its coil circuit 102 is energized, the armature members swinging back to its outer position when the circuit 102 is broken. 115

When the armature member is in its outer position it is engaged by any approaching lug 98 upon the turn-table which deflects the rocker and stops rotation of the turn-table, so that the lugs cannot pass the armature member except during periods in which the coil 102 is energized. 120

The turn-table is thus stopped automatically each time one of the lugs moves into position to engage the armature, that is, each time one of the units comes around to the set position at which grinding must have been completed, unless the magnet is energized, 125 130

the stoppage of the turn-table not affecting the operation of the different grinding units.

The electric circuit through the magnet includes spaced slide contacts 103 and 104 which connect at contacts 105 and 106 successively for short periods into the circuits 107 on the turn-table at the individual units each of which includes a member 90 adapted when energized to effect a return of the feed

10 wheel 49 to its initial position.

The contacts 105 and 106 carried by the turn-table at each grinding unit are presented across the contacts 103 and 104 when the different units are passing a predetermined position that is somewhat before the position for unloading at 27 and the circuits 107 on the turn-table at the different grinding units also includes open contacts closed by a determinative movement of the gauge 28 or

20 28' when the work piece reaches finish size.

The magnet 101 can thus not be energized unless and until the piece has come to finish size and also unless and until the turn-table has brought the unit to the selected position 25 so that the turn-table automatically stops any time a piece comes to the selected position without having been yet ground to size and goes on automatically as soon as the piece comes to size, the contacts 103 and 104 registering with the contacts 105 and 106 during the periods of stoppage.

In operation the work pieces are loaded into the successive work-holders as they pass a loading point 26, Figure 1. This loading 35 is preferably automatic but may be by hand.

After each unit is loaded, traverse grinding begins at the unit and continues with an automatic screw feed that is effected in the mechanism illustrated by vertical reciprocation 40 of the rod 37 of Figure 2 operating the ratchet feed rocker 38. This reciprocation is conveniently effected by suitable connections to the traversing wheel unit, as described in detail in the McDonough patent.

45 Traverse grinding continues until the gauge member 28 or 28' makes a determinative movement by reason of the work piece having reached the desired size, which movement is used to close an electric circuit 50 through a member 108 for raising the wheel unit from the work as described in McDonough patent, and the same or other electric circuit through a member 53 for stopping the inward feed between the work piece and

55 wheel.

In Figure 2 this closure is effected at the contacts 61 and 62 while in the structure of Figure 3 it is effected at the contacts 61' and 36.

60 Optionally a circuit through the magnet 52 may be closed by an earlier and lesser movement of the gauge to reduce the rate of feed of the feed screw by energizing the magnet 52. This optional circuit is necessary where there are two feeds such as those de-

scribed by McDonough and illustrated in Figures 2 and 3.

In Figure 2 this earlier closure takes place at the contacts 59 and 60 while in the structure of Figure 3 it takes place at the corresponding contacts 60' and 36.

Either before or after the piece comes to size with a resultant stoppage of further ratchet feed of the feed wheel 49 and a raising of the grinding wheel out of the work 70 piece, due to the determinative movement of the gauge 28 or 28', it reaches the selected point a little before the unloading position at which the slide contacts 103 and 104 register with the contacts 105 and 106 on the 75 turn-table and one of the lugs 98 of the turn-table during this registry reaches position to stop rotation of the turn-table unless and until the magnet 101 is energized.

If the magnet 101 has not yet been energized the turn-table stops leaving the contact members 103 and 104 still engaging the members 105 and 106, while traverse grinding continues until the piece comes to size when the circuit closes by the determinative 85 movement of the gauges, through the magnet 90 90 to effect spring return of the feed wheel and through the magnet 102 to start the turn-table.

If the piece has already come to size by 95 the time the lug 98 is in position to stop the turn-table, the turn-table does not stop because the magnet 101 is energized and draws back the armature member 97 out of the path 100 of the lug 98 as soon as the contact members 102 and 103 register with the contacts 105 and 106, and at the same time energizes the magnets 90 and 53 to effect the spring-return of the feed wheel.

Desirably unloading and loading are automatic, the character of the loading and unloading devices being merely of any suitable kind such, for example, as described by me in several copending applications.

The combination between an automatic unloading or an automatic loading device with the automatic spring-return of the feed screw is particularly advantageous in that it avoids danger of smashing the machine by starting 105 mechanism for traverse grinding before the feed screw has moved into a position to avoid head-on engagement between the ends of the grinding wheel and the top of the work piece.

110 In view of my invention and disclosure variations and modifications to meet individual whim or particular need will doubtless become evident to others skilled in the art, to obtain all or part of the benefits of my invention without copying the structure shown, and I, therefore, claim all such in so far as 115 they fall within the reasonable spirit and scope of my invention.

120 Having thus described my invention, what 125

I claim as new and desire to secure by Letters Patent is:—

1. In a multiple grinding machine, a turn-table and grinding units at spaced intervals therearound, each unit comprising a work-holder, a grinding wheel, a shaft adapted to rotate in opposite directions to change the relative alinement of the wheel and holder, a ratchet mounted on the feed shaft, an anchor wheel adjacent the ratchet wheel and adapted to rotate, a spiral spring connected at one end to the anchor wheel and at the other end to the ratchet wheel, a spring click yieldably holding the anchor wheel in any set position and permitting angular movement of the anchor wheel with respect to the ratchet wheel, two stops determining the initial angular position of one wheel with respect to the other, one fastened to each of the wheels.
2. In a multiple grinding machine, a turn-table and grinding units at spaced intervals therearound, each unit comprising a work-holder, a grinding wheel, a shaft adapted to rotate in opposite directions to change the relative alinement of the wheel and holder, a ratchet wheel mounted on the feed shaft, an anchor wheel adjacent the ratchet wheel and adapted to rotate, a spiral spring connected at one end to the anchor wheel and at the other end to the ratchet wheel, a spring click yieldably holding the anchor wheel in any set position and permitting angular movement of the anchor wheel with respect to the ratchet wheel, two stops determining the initial angular position of one wheel with respect to the other, one fastened to each of the wheels and an adjustment of the initial tension of the spiral spring.
3. In a multiple grinding machine, a turn-table and grinding units at spaced intervals therearound, each unit comprising a work-holder, a grinding wheel, a shaft adapted to rotate in opposite directions to change the relative alinement of the wheel and holder, a ratchet wheel mounted on the feed shaft, an anchor wheel adjacent the ratchet wheel and adapted to rotate, a spiral spring connected at one end to the anchor wheel and at the other end to the ratchet wheel, a spring click yieldably holding the anchor wheel in any set position and permitting angular movement of the anchor wheel with respect to the ratchet wheel and two stops determining the initial angular position of one wheel with respect to the other, one fastened to each of the wheels and means for adjustably limiting the forward feed of the ratchet wheel with respect to the anchor wheel.
4. In a multiple grinding machine, a turn-table and grinding units at spaced intervals therearound, each unit comprising a work-holder, a grinding wheel, a shaft adapted to rotate in opposite directions to change the relative alinement of the wheel and holder, a ratchet wheel mounted on the feed shaft, an

anchor wheel adjacent the ratchet wheel and adapted to rotate, a spiral spring connected at one end to the anchor wheel and at the other end to the ratchet wheel, a spring click yieldably holding the anchor wheel in any set position and permitting angular movement of the anchor wheel with respect to the ratchet wheel, two stops determining the initial angular position of one wheel with respect to the other, one fastened to each of the wheels, 75 an adjustment for the initial tension of the spiral spring, and an adjustable stop adapted to adjustably limit the forward feed of the ratchet wheel with respect to the anchor wheel.
